LOCKING MECHANISM

Gerrit D. Hill, Rochester, N. Y., assignor to
 Sargent & Greenleaf, Inc., Rochester, N. Y.,
 a corporation of New York

Application October 15, 1932, Serial No. 637,962

13 Claims. (Cl. 70—53)

The present invention relates to lock mechanism and has for its object to provide an improved combination lock embodying a simplified and compact arrangement of parts designed to protect the closures of different receptacles, compartments, and the like.

A further object of the invention is to provide an improved lock of this class designed to facilitate quick operation of the combination whereby to reduce the time required to open the various receptacles or compartments to which the locks may be applied.

A further object of the invention is to provide an improved combination lock having different bolt protecting mechanisms corresponding to different combinations and arranged to be released by operating either combination.

A further object of the invention is to provide an improved combination lock for protecting a bolt or other locking means embodying a plurality of sets of tumblers corresponding to different combinations and having fence means for each set of tumblers in which arrangement one of the tumblers is effective to control the movement of the bolt under operation of either combination.

A further object of the invention is to provide a combined individual and master combination lock whereby various similarly constructed locks may each be set up for operation by different individual combinations and also successfully operated by a master combination common to all of the locks.

A further object of the invention is to provide an improved combination lock in which different tumbler mechanisms are provided with corresponding fence means and are mounted in a barrel for controlling a bolt movable therein and in which arrangement one of the tumblers is adapted to control the movements of the different fence means and the bolt upon operation of either combination.

To these and other ends the invention resides in certain improvements and combinations of parts, all as will be hereinafter more fully described, the novel features being pointed out in the claims at the end of the specification.

In the drawings:

Fig. 1 is a front elevation illustrating the application of the lock to a closure;

Fig. 2 is a top plan view of the same;

Fig. 3 is a rear elevation partly in section showing the bolt in locking engagement with the keeper;

Fig. 4 is a part sectional elevation showing the

application of the lock casing and the operating dial to the closure;

Fig. 5 is a front view of the lock shown removed from the closure;

Fig. 6 is a front view of the combined tumbler 5 and fly by means of which the master combination can be changed from time to time;

Fig. 7 is a rear elevation of the lock barrel or casing with the cover plate removed showing the bolt in locking position and the fence elements 10 withdrawn from the notches of the tumblers;

Fig. 8 is a similar view in which the notches of the individual set of tumblers have been alined by the successful operation of the individual combination, the corresponding fence being shown 15 within said notches and the bolt being ready for release;

Fig. 9 is a similar view showing the bolt in released position;

Fig. 10 is a rear view of the tumbler barrel with 20 the tumbler retaining element and tumblers omitted;

Fig. 11 is a side view of the barrel as seen from the top of Fig. 10;

Fig. 12 is a rear elevation of the barrel with 25 the cover plate removed in which the notches of the master set of tumblers have been alined by the operation of the master combination, the corresponding fence being shown within said notches and the bolt being ready for release; 30

Fig. 13 is a similar view showing the bolt in released position;

Fig. 14 is a transverse sectional elevation through the lock casing or barrel showing the relationship of the two sets of tumblers and the 35 fence elements corresponding thereto;

Fig. 15 is a rear elevation of the tumbler barrel with the tumblers of one set shown in registering relation therein;

Fig. 16 is a transverse section through the lock 40 taken approximately on line 16a—16a of Fig. 12;

Fig. 17 is a view illustrating the tumblers and spacing members therefor corresponding to the master combination;

Fig. 18 is a similar view illustrating the tumblers and spacing members therefor corresponding to the individual combination;

Fig. 19 is a side view of a driving unit for the master and individual sets of tumblers which is keyed to the spindle as shown in Fig. 16; 50

Fig. 20 is a front elevation of the bolt showing the fence elements thereon;

Fig. 21 is a longitudinal section through the bolt taken on line 21a—21a of Fig. 20;

Fig. 22 is a fragmentary sectional view illus- 55

trating the operating position of the change key with respect to one of the tumblers corresponding to the master combination;

Fig. 23 is a similar view showing the operating 5 position of the change key corresponding to the individual set of tumblers;

Fig. 24 is a view of a portion of the change key shown in Fig. 22; and

Fig. 25 is a view of a portion of the change key 10 shown in Fig. 23.

The same reference numerals throughout the several views indicate the same parts.

The present invention comprises locking mechanisms for guarding the doors or closures of various receptacles, compartments, and the like, and particularly those of the type which are generally grouped together for use by different individuals and usually under the control of an attendant with authority to open the same when desired.

20 The invention embodies a locking or protecting mechanism of the permutation or combination type which includes a tumbler arrangement under the control of suitable operating means such as a dial or its equivalent. At least one of the 25 tumbler mechanisms and the controlling dial and spindle therefor is designed for quick operation, as by a partial revolution of the dial for each of the setting up operations, or by a direct movement from one number of the combination to 30 another, thus permitting the combination to be operated in a minimum of time.

One application of the present locking mechanism is to the drawers of school desks, each of which may be provided with the same type of 35 lock, the different locks being set for release by the operation of different individual combinations entrusted to the different students to which the desks are assigned and all of the locks being designed for release by the operation of a master 40 combination unknown to the students and entrusted to one or more persons having authority to open the drawers of the various desks from time to time. One advantage of this arrangement is that an officer or attendant when desiring 45 to open the drawers or other closures, instead of having to remember all of the different individual combinations or having to refer to a list of the same may quickly and readily open any or all of the closures by the operation of a single master 50 combination entrusted to him.

Referring to the drawings, 10 represents a portion of a receptacle or container of any preferred type having a suitable closure 11 constructed in any desired manner and to which one form of 55 the improved lock mechanism is shown applied as indicated in Fig. 3. In this arrangement the wall of the receptacle is provided with a keeper 12 for receiving the locking bolt 13 of the particular lock shown. The closure 11 may constitute the drawer of a desk or the door of a 60 locker or any preferred form of protecting means for safe-guarding various articles. The closure 11 is recessed at its rear side to receive the locking mechanism as shown in Fig. 16. The locking mechanism is carried by a suitable support 65 preferably comprising a casing in the form of a barrel 14 having a rear end cover plate 15 provided with a forwardly extending plate-like portion 15a disposed substantially flush with the 70 top of the closure as shown in Fig. 4 and serving as guide means for the bolt 13.

The cover plate 15 is connected with the barrel by means of suitable bolts or rivets 16 and is also connected with the closure 11 by means of 75 screws 17 extended through holes 11a in the plate,

shown in Fig. 5. The screws take into lugs 18 extending rearwardly from the escutcheon plate 19 into openings formed in the wall of the closure 11 as shown in Fig. 16.

The escutcheon plate 19 is provided with the 5 usual index 20 for cooperation with the numbers on the dial 21 for operating the spindle 22 which is rotated to effect successful operation of the different tumbler mechanisms as hereinafter described. The escutcheon plate is also provided 10 with index marks 20a and 20b for use when operating the dial to change the individual and master combinations as described hereinafter.

The two sets of tumblers corresponding to the master and individual combinations are shown 15 respectively in Figs. 17 and 18 and each set is rotatably supported within the barrel through engagement of the peripheral portions of the tumblers with the surrounding wall of the barrel 20 in which the bolt 13 is slidably mounted.

The tumblers of the master combination and their spacing elements, in the order in which they are placed within the barrel from front to rear, are indicated by the reference characters 23 to 28 25 inclusive, as shown in Fig. 17, while the tumblers and the spacing elements of the individual combination are indicated, from front to rear, by the reference characters 29 to 35 inclusive, as shown in Fig. 18, the member 36 being the retaining 30 element for the various tumblers and spacing elements.

It will be seen that there are three tumblers in the set corresponding to the master combination and four in the set corresponding to the individual combination, but it will be understood that 35 the number of either set may be varied as desired.

The master tumblers are indicated by the reference characters 23, 25, and 27 and the individual tumblers by the reference characters 29, 31, 33 40 and 35. The various spacing elements located 45 between the tumblers are held against rotation by means of the lugs 37 thereon which are extended within a slot 38 formed in the wall of the barrel as shown in Fig. 15, this being true also of the yieldable or spring-like retaining element 15 50 36 which is sprung into a groove 39 formed in the wall of the barrel as shown in Figs. 10 and 14.

All of the tumblers, except the fence operating 55 and bolt actuating tumbler 35, are mounted for rotation relative to the spindle 22 in the setting 60 up operations of the different combinations. A driving unit, Fig. 19, is provided for the two sets 65 of tumblers and comprises a tubular section 40 having bearings 41 and 42 at its front and rear ends respectively, which are journaled in the front and rear walls of the barrel 14, as shown 70 in Fig. 16. The tubular member 40 has an enlarged annular portion 43 provided with teeth 43a which intermesh with similar teeth on the driving section 44 of the unit which is sleeved on the section 40 and held in adjusted position thereon by a spring 45 interposed between the section 44 and a collar 46 fixed on the section 40. The tubular section 40 is adapted to receive the spindle 22 and is provided with a pin 47 which extends within a slot 48 formed in the spindle, as shown in Fig. 16, whereby upon rotation of the spindle the parts 43 and 44 of the driving unit 75 will likewise be rotated. The slot 48 in the spindle permits the latter and the dial thereon to be 80 readily removed from the lock upon removal of the escutcheon plate from the wall of the closure.

The front tumbler 23 of the master set is provided with a tongue-like portion 23a by which the tumbler is driven through engagement of 75

said portion with a lug 49 on the annular portion 43 of the driving unit through which the pin 47 is preferably extended, as shown in Fig. 16. The tumbler 23 serves to drive the next adjacent tumbler 25 through engagement of the pin 23b on the former with the pin 25b on the latter. The tumbler 27 has a fly 27a rotatably adjustable thereon to permit of a change in the set-up of the master combination when desired. The tumbler 27 is 10 driven through engagement of the pin 25c on the tumbler 25 with the part 27b of the fly. The pin 25c on the tumbler 25 is preferably made integral with the pin 25b of said tumbler as shown in Fig. 16. The fly is held in position upon the tumbler 27 by a retaining ring 27c, the ring having a hub-like portion extended through the tumbler and provided with a flange engaging the rear side of the tumbler as shown in Fig. 16. The part 27b of the fly is formed of spring material 15 and has an offset portion 27d which takes into one or another of the openings or depressions 27e formed in the tumbler 27 as shown in Fig. 6. The fly is held in the different positions to which it may be adjusted in changing the master combination by frictional engagement of the offset portion 27d with the wall of the tumbler 27 when said offset portion is within one of the openings 27e. The method of effecting relative adjustment of the fly and the tumbler to change the master 20 combination will be described hereinafter.

The master tumblers 23 and 25 are separated by the spacing element 24 and the tumblers 25 and 27 by the spacing element 26, the latter being made relatively thick, as shown in Fig. 16, in view 25 of the mounting of the fly and its retaining element on the tumbler 27.

The individual set of tumblers and the interposed spacing elements are mounted within the barrel, from front to rear, in the order indicated 30 by the reference characters 29 to 35 inclusive in Fig. 18. In this arrangement the tumbler 29 is driven through engagement of the tongue 29a thereon with the lug 50 on the sleeve 44 of the driving unit shown in Fig. 19. This lug also 35 serves to drive the tumbler 31 through its engagement with one or the other of the tongues 31a thereon and likewise operates to drive the tumbler 33 through engagement with one or the other of the tongues 33a on said tumbler. The lug 50 also drives the rearmost tumbler 35 by being projected within the notch 35a formed therein. The tumbler 35 which operates the bolt and the fence elements, as described hereinafter, is 40 directly driven by the spindle and the dial thereon whenever the latter is rotated to operate either combination, it being understood that the driving unit, Fig. 19, is considered as a part of the spindle.

As previously stated the member 36, shown in 45 Fig. 18, constitutes a retainer for the tumblers and spacing elements mounted within the barrel and is secured by springing it into the groove 39 of the barrel as shown in Fig. 14.

The tumblers 23, 25, and 27 of the master set 50 are notched at 23f, 25f, and 27f, respectively, as shown in Fig. 17, and the notches are brought into alignment by turning the dial to successfully operate the master combination.

The tumblers 29, 31, and 33 of the individual 55 set are notched at 29f, 31f, and 33f, respectively, as shown in Fig. 18, while the bolt operating tumbler 35 which is common to both sets is notched as shown at 35f.

The notches of the tumblers 29, 31, and 33 of 60 the individual set, through cooperation of the

driving lug 50, with the inwardly projecting tongues on said tumblers, are brought into registry by a partial revolution of the dial for each setting up operation required in the successful operation of the combination, which also requires that the notch in the bolt operating tumbler 35 be aligned with the notches in the remaining tumblers of either set. 5

The bolt 13 is guided within the barrel through engagement of its laterally extending portions 10 51 with the opposite guides 52 formed on the barrel.

The bolt has mounted on its opposite sides the fence elements 53 and 54 arranged to swing upon a common pivot member 55 suitably secured upon the bolt, the fence 53 corresponding to the master set of tumblers and the fence 54 corresponding to the individual set of tumblers. The fence 53 is provided with a portion 53a adapted to take into the notches of the master set of tumblers 20 and with a portion 53b arranged to move into the notch 35f of the bolt operating tumbler 35 upon successful operation of the master combination. The fence 53 is cut away at 53c to clear the individual set of tumblers when moving 25 into the notches of the master set.

The fence 54 is provided with a portion 54a arranged to move within the notches of the individual set of tumblers and also within the notch 35f of the bolt operating tumbler 35 when said 30 tumbler notches are aligned one with another. A spring 56, suitably secured upon the wall of the barrel, serves to move the portion 53a of the fence 53 within the notches of the master set of tumblers upon successful operation of the 35 master combination and a spring 57 operates to move the portion 54a of the fence 54 within the notches of the individual set of tumblers as well as within the notch 35f of the bolt operating tumbler 35 upon successful operation of the individual combination. 40

The fence 53 is slotted at 58 to receive the pivot member 55. By thus slotting the fence 53 relative movement between the latter and the bolt in a vertical direction is permitted whereby the 45 bolt may be moved to release position upon successful operation of one set of tumblers while the other set and its fence remain in normal bolt protecting position. With the bolt in the locking position shown in Fig. 7, the fence 53 will rest 50 on the relatively inclined shoulder 59 formed by cutting away the wall of the barrel, as best shown in Fig. 10, and in this position the bolt will be supported by the fence 54 through engagement of the portion 54a thereof with the underlying 55 portion of the fence 53 in which position the parts are shown in Fig. 7.

Upon successful operation of the individual combination, the fence 54 will move into the notches of the tumblers corresponding thereto 60 as indicated in Fig. 8. The bolt can then be moved to the release or unlocked position, shown in Fig. 9, in which the fence 53 remains seated upon the shoulder 59 of the barrel while the pivot member on the bolt will occupy a position 65 within the lower end of the slot 58.

If on the other hand, the master combination is successfully operated, the fence 53 will move into the notches of the master set of tumblers as shown in Fig. 12, thus permitting the bolt to 70 be moved to release position, as shown in Fig. 13 in which position the fence 54 will ride on the peripheral portions of the tumblers of the individual set as indicated by its dotted line position in Fig. 12.

With the bolt in either of the unlocked positions shown in Figs. 9 and 13, the turning of the dial to destroy the combination will cause a pin 60 on the tumbler 35 to move into engagement with an abutment or lug 61 on the bolt to raise or move the latter to locking position.

In this operation a cam 62 on the tumbler 35 will engage the fence 54 if the bolt has been released by operation of the individual combination as shown in Fig. 9 and will move said fence out of the notches of the individual set of tumblers at the same time that the pin 60 on the tumbler 35 is operating through engagement with the lug 61 on the bolt to return the latter to locking position. However, if the bolt has been released by operation of the master combination as indicated in Fig. 13, then upon operating the dial to destroy the combination and to return the bolt to locking position, the cam 62 of the tumbler 35 will engage and move the fence 53 out of the notches of the master set of tumblers thus restoring the fence to the position shown in Fig. 7 in which it rests upon the shoulder 59 of the barrel and in position to engage the bottom of the fence 54 whereby to support the bolt in locking position.

It will be seen, therefore, that in returning the bolt to locking position that the pin 60 on the tumbler 35 when moving in engagement with the lug 61 on the bolt operates independently of the fence elements 53 and 54 which are restored to bolt protecting or locking position by the movement of the cam 62 in engagement therewith.

The bolt is slotted at 63 to permit the rear end of the driving unit shown in Fig. 19 to project therethrough as shown in Fig. 16.

The wall of the barrel is recessed or cut away at 64 to afford clearance for the head of the pivot member 55 on which the fence elements are mounted as best shown in Figs. 11 and 14.

40 The barrel has an opening 65 formed in its side wall for the reception of either of the change keys 66 or 67, shown in Figs. 24 and 25, provided for changing the master and individual combinations, respectively. The key 66 has a lug 68 thereon adapted to engage an abutment 69 on the wall of the barrel which affords a stop for limiting the turning movement of the key within the opening 65 and which also serves to limit the turning movement of the key 67 through engagement of the stop with a lug 70 on said key. The key 68 has a bit 66a thereon for engaging the tumbler 27 within the notch thereof, as shown in Fig. 22, when a change in the master combination is to be made.

55 Likewise the key 67 is provided with a bit 67a arranged to engage the tumbler 35 within the notch thereof as shown in Fig. 23 when a change in the individual combination is to be made.

In changing the master combination the key 66 will be inserted within the slot 65 and given a quarter of a turn until it occupies the position shown in Fig. 22. Before doing this, however, the dial is turned to the right at least four revolutions, after which it is brought to rest when the first number of the old combination is in registry with the index mark 29b on the escutcheon plate. The key at this time will have the lug 68 in engagement with the abutment 69 on the barrel in which position the key is held by the operator. 70 The bit 66a on the key will engage the tumbler 27 within the notch thereof so that the tumbler will be held against rotation by the key. The dial will then be turned slowly toward the right and through engagement of the pin 25c on the tumbler 75 25 with the portion 27b of the fly the latter will

be rotated. By counting the clicks of the fly when the part 27d thereof passes from one of the openings 27e in the tumbler to another, the operator will be able to readily effect the desired change in the master combination.

In changing the individual combination the notch in the tumbler 35 is brought into registry with the key opening 65 formed in the wall of the barrel by turning the dial to align the last number of the old combination with the index mark 20a 10 on the escutcheon plate, after which the key is inserted in the opening 65 and given a quarter turn until the lug 70 thereon moves into engagement with the stop 69 on the barrel. The key is then held while at the same time the dial is 15 turned slowly toward the left which results in rotation of the part 48 of the tumbler driving unit since the part 44 at this time is held against rotation by the tumbler 35 which in turn is held by the key 67. In this turning movement the 20 clicking of the teeth between the parts 40 and 44 of the driving unit will be audible, or can be detected by the sense of touch, each click indicating an advance of one number over the previous number of the combination. In this way one or 25 more numbers of the individual combination can be readily changed to afford the desired new combination and when the parts have been set to correspond to the numbers chosen the key is withdrawn from the barrel.

30 In the operation of the individual combination by the user of the desk the dial is turned to the left to position the first number of the combination in registry with the index 20. It is then rotated to the right for a partial revolution to position the second number of the combination in registry with said index and is then turned to the left a partial revolution to position the third number in registry with the index after which another partial revolution of the dial to the right 40 completes the operation by aligning the fourth number with the index, whereby the fence corresponding to said set is permitted to move with 45 in the notches thereof to release the bolt.

50 In the operation of the master combination the dial is rotated in the usual manner to line up the notches of the master set of tumblers to permit the fence corresponding to said tumblers to move into the notches thereof.

I claim:

1. Lock mechanism comprising supporting means, a locking element movable thereon and provided with an abutment, individual permutation mechanisms for protecting the locking element, each including tumblers and a fence element, said fence elements adapted for protecting the locking element against release through co-operation of one with another, common operating means for said permutation mechanisms disposed axially thereof, and means on one of the tumblers of one permutation mechanism adapted to co-operate with the abutment on the locking element to move the latter to locking position following successful operation of either of said mechanisms. 60 65

2. A combination lock comprising supporting means, a bolt movable thereon and provided with an abutment, axially disposed individual sets of notched rotary tumblers on the supporting means corresponding to different combinations, operating means for said tumbler sets, fence elements for guarding the bolt each corresponding to one set of tumblers and movable into the notches thereof upon successful operation of the combination corresponding thereto, said fence elements 70 75 80 85 90 95

- adapted for cooperation to hold the bolt against release when it is in locking position and operable one independently of another to release the bolt and means on one of the tumblers of one set 5 adapted to engage the abutment on the bolt to move the latter in one direction after successful operation of either combination.
3. A combination lock comprising supporting means having a shoulder thereon, a bolt movable on the supporting means and provided with an abutment, individual sets of notched rotary tumblers on the supporting means corresponding to different combinations, operating means for said tumbler sets, fence elements arranged through 10 cooperation one with another and with the shoulder on the supporting means to hold the bolt against release upon destroying either combination, each fence element corresponding to one set of tumblers and movable into the notches thereof upon successful operation of the combination corresponding thereto, means on one of the tumblers of one set adapted upon destroying either combination to move the corresponding fence out of the notches of its said tumblers, and 15 means on the last mentioned tumbler adapted to engage the abutment on the bolt to move the latter to locking position upon destroying either combination.
4. A combination lock comprising supporting means provided with a shoulder, a bolt slidable upon and guided by the supporting means and provided with an abutment, individual sets of notched rotary tumblers on the supporting means corresponding to different combinations, operating 20 means for said tumbler sets, fence elements individual to said sets of tumblers movable upon the bolt one adapted to engage the shoulder on the supporting means when the bolt is in locking position and cooperating one with another and with the supporting means to hold the bolt in said position upon destroying either combination, the bolt being released upon successful operation of either set of tumblers by the movement of the corresponding fence within the notches thereof, and means on one of the tumblers of one set 25 adapted to engage the abutment on the bolt to move the latter to locking position upon destroying either combination.
5. A combination lock comprising a barrel, a bolt slidably mounted within the barrel, two sets of notched tumblers rotatably supported within the barrel through engagement of the peripheral portions with the surrounding wall of the barrel, one of the tumblers being common to both sets, 30 separate fence elements within the barrel each arranged to move into the notches of the tumblers to which it corresponds and into the notch of said last mentioned tumbler upon successful operation of the corresponding combination, and devices on said last mentioned tumbler one operating upon destroying the combination to return the bolt to locking position and another to move either fence element out of the tumbler notches corresponding thereto, said fence elements 35 cooperating one with another and with the barrel to hold the bolt at locking position upon destroying either combination.
6. A combination lock comprising a barrel, a bolt slidably mounted within the barrel, two sets of notched tumblers rotatably supported within the barrel through engagement of their peripheral portions with the surrounding wall of the barrel, one of the tumblers being common to both sets and operatively associated with the bolt, separate fence elements within the barrel each ar- 40 ranged to move into the notches of the tumblers to which it corresponds upon successful operation of the combination corresponding thereto, said bolt operating tumbler upon destroying the combination serving to simultaneously move the bolt to locking position and either fence element out of the tumbler notches corresponding thereto, said fence elements cooperating one with another and with the barrel to hold the bolt against release from locking position upon destroying either combination.
7. A combination lock comprising a barrel, two sets of tumblers corresponding to different combinations rotatably supported within the barrel through engagement of their peripheral portions 45 with the surrounding wall of the barrel, a bolt movable relative to the barrel, relatively movable fence elements mounted upon the bolt one for each set of tumblers, said fence elements adapted to cooperate one with another and with the barrel to hold the bolt against release upon destroying either combination, each fence element cooperating with its set of tumblers to release the bolt upon successful operation of the corresponding combination, and rotatably mounted means 50 within the barrel extending through a plurality of the tumblers and movable relative thereto to condition either set of tumblers for movement of its corresponding fence element to bolt releasing position.
8. A combination lock comprising a barrel, two sets of tumblers corresponding to different combinations rotatably supported within the barrel through engagement of their peripheral portions with the surrounding wall of the barrel, 55 a bolt slidably mounted within the barrel, relatively movable fence elements associated with the bolt one for each set of tumblers, said fence elements adapted to cooperate one with another and with the barrel to hold the bolt against release upon destroying either combination, each fence element cooperating with its set of tumblers to release the bolt upon successful operation of the corresponding combination, and common operating means for said sets of tumblers including a 60 dial movable to operate one of the combinations by a partial revolution of the dial in its movement from one setting up position to another.
9. A combination lock comprising a barrel, two sets of tumblers corresponding to different combinations rotatably supported within the barrel through engagement of their peripheral portions with the surrounding wall of the barrel, a bolt 65 slidably mounted within the barrel and provided with an opening, fence elements pivotally mounted upon the bolt to swing about a common center, one for each set of tumblers, said fence elements adopted to cooperate one with another and with the barrel to hold the bolt against release upon destroying either combination, each fence element cooperating with its set of tumblers to release the bolt upon successful operation of the corresponding combination, a rotatably mounted member within the barrel extending axially thereof through the opening in the bolt and 70 having parts adapted to effect rotation of said different sets of tumblers to successfully operate the combinations corresponding thereto, and a dial for operating said member.
10. A combination lock comprising a barrel, 75 two sets of tumblers corresponding to different combinations rotatably supported within the barrel through engagement of their peripheral portions with the surrounding wall of the barrel, a bolt slidably mounted within the barrel,

- relatively movable fence elements mounted upon the bolt one for each set of tumblers, said fence elements adapted to cooperate one with another and with the barrel to hold the bolt against release upon destroying either combination, each fence element cooperating with its set of tumblers to release the bolt upon successful operation of the corresponding combination, means on one of the tumblers cooperating with the bolt independently of the fence elements to move the bolt to locking position upon destroying either combination, and means rotatable within the barrel relative to said different sets of tumblers for moving the tumblers to successfully operate the combinations corresponding thereto.
11. A combination lock comprising a barrel, two sets of tumblers corresponding to different combinations rotatably supported within the barrel through engagement of their peripheral portions with the surrounding wall of the barrel, a bolt slidably mounted within the barrel provided with an opening and having a laterally projecting operating part, relatively movable fence elements associated with the bolt one for each set of tumblers, said fence elements adapted to cooperate one with another and with the barrel to hold the bolt against release upon destroying either combination, each fence element cooperating with its set of tumblers to release the bolt upon successful operation of the corresponding combination, and a rotatably mounted member within the barrel extending axially thereof through the opening in the bolt and provided with parts adapted to effect rotation of said different sets of tumblers to successfully operate the combinations corresponding thereto, one of said tumblers being adjacent to and substantially parallel with the bolt and having a projecting part for engaging the operating part on the bolt to move the bolt to locking position upon destroying either combination by rotation of said member in one direction.
12. A combination lock comprising a barrel, two sets of tumblers corresponding to different combinations rotatably supported within the barrel through engagement of their peripheral portions with the surrounding wall of the barrel, a bolt slidably mounted within the barrel to protect the bolt against release upon destroying either combination, each fence element cooperating with its set of tumblers to release the bolt upon successful operation of the corresponding combination, operating means for conditioning either set of tumblers for movement of its corresponding fence element to bolt releasing position, an abutment on the bolt, a part on one of the tumblers adapted for engagement with said abutment to move the bolt to locking position upon destroying either combination, and a part on said last mentioned tumbler operating when the combination is being destroyed to restore the fence elements to bolt protecting position.
13. A combination lock comprising a barrel, having end closing walls, two sets of tumblers corresponding to different combinations rotatably supported within the barrel through engagement of their peripheral portions with the surrounding wall of the barrel, a slotted bolt slidably mounted within the barrel between the end walls thereof, relatively movable fence elements associated with the bolt within the barrel one for each set of tumblers adapted through cooperation one with another and with the barrel to hold the bolt against release upon destroying either combination, each fence element cooperating with its set of tumblers to release the bolt upon successful operation of the corresponding combination, a rotatably mounted device extending through the tumblers and the slotted bolt and having its opposite ends journaled in the end walls of the barrel, said device being operative to condition either set of tumblers for movement of its corresponding fence element to bolt releasing position, and a dial for operating said device.
